(57) **CLAIM**

The ornamental design for a foot pedal guide for a drum pedal, as shown and described.

DESCRIPTION

FIG. 1 is a front view of a foot pedal guide for a drum pedal; FIG. 2 is a right side view thereof, the left side view being a mirror image;

FIG. 3 is a top view thereof;

FIG. 4 is a bottom view thereof;

FIG. 5 is an isometric view thereof; and,

FIG. 6 is an isometric view thereof showing the foot pedal guide for a drum pedal in a condition of use.

The features drawn in broken lines in FIG. 6 show a drum pedal associated with the foot pedal guide for a drum pedal in a condition of use, and which forms no part of the claimed invention.
